(57) **CLAIM**

We claim the ornamental design for a connecting end portion of a knitting needle, as shown and described.

DESCRIPTION

FIG. 1 is a front view showing a connecting end portion of a knitting needle according to our design;

FIG. 2 is a rear view thereof;

FIG. 3 is a left side view thereof;

FIG. 4 is a right side view thereof;

FIG. 5 is a top plan view thereof;

FIG. 6 is a bottom plan view thereof; and,

FIG. 7 is a cross-sectional view taken along arrow lines 7-7 between chain lines 7-7 in FIG. 1.

The broken lines depict portions of the article that form no part of the claimed design.

1 Claim, 5 Drawing Sheets
